UNITED STATES PATENT OFFICE.

BARTOW A. WARLICK, OF ATLANTA, GEORGIA.

WINDOW.

No. 897,435.

Specification of Letters Patent.

Patented Sept. 1, 1908.

Application filed February 8, 1908. Serial No. 415,001.

To all whom it may concern:

Be it known that I, BARTOW A. WARLICK, a citizen of the United States, residing at Atlanta, in the county of Fulton and State 5 of Georgia, have invented a new and useful Window, of which the following is a specification.

This invention relates to windows and has for its object to provide a window in which 10 the frame and rails of the sliding sashes are constructed of sheet metal thereby to reinforce and strengthen the window and render the same fire proof.

A further object of the invention is to 15 provide the vertical rails of the sliding sashes with spaced flanges for engagement with the adjacent window stops, the latter being provided with lateral guide lips which bear against the sashes thereby to reduce friction 20 to a minimum and render the window practically weather proof.

A further object is to form the meeting rails of one of the sashes with a longitudinal flange which bears against the inclined face 25 of the meeting rail of the adjacent sash when said sashes are in closed position, thereby to produce an intermediate air space or chamber.

A further object is to so arrange the sashes 30 with respect to the window frame as to form vertical air cushions on opposite sides of the window and further to provide improved means for securing the stops in position on said frame.

A still further object of the invention is 35 generally to improve this class of devices so as to increase their utility, durability and efficiency.

Further objects and advantages will appear 40 in the following description, it being understood that various changes in form, proportions and minor details of construction may be resorted to within the scope of the appended claims.

In the accompanying drawings forming 45 a part of this specification: Figure 1 is a side elevation of a portion of a fire proof window constructed in accordance with my invention. Fig. 2 is a vertical sectional view of 50 the same. Fig. 3 is a detail sectional view taken on the line 3—3 of Fig. 2. Fig. 4 is a detail sectional view taken on the line 4—4 of Fig. 1. Fig. 5 is a similar view taken on the line 5—5 of Fig. 1. Fig. 6 is a sectional 55 view taken on the line 6—6 of Fig. 1. Fig. 7 is a sectional view taken on the line 7—7 of

Fig. 1. Fig. 8 is a sectional view taken on the line 8—8 of Fig. 1, and, Fig. 9 is a sectional view taken on the line 9—9 of Fig. 2.

Similar numerals of reference indicate corresponding parts in all of the figures of the drawings.

The improved window forming the subject matter of the present invention comprises a hollow supporting frame or casing 65 5 preferably formed of sheet metal and in which is mounted for sliding movement the sashes 6 and 7. Extending transversely across the side members of the frame or casing is an intermediate partition 8 forming 70 pockets or compartments 9 for the reception of the sliding weights or counter balances 10. The side members are reinforced and strengthened by the provision of metallic braces 11, which latter extend the entire 75 width of the frame and are riveted or otherwise rigidly secured to the metal forming the inner section of the window frame, as indicated at 12. The metal forming the outer section of the frame is lapped over the adjacent ends of the inner section at 13, said outer section being provided with an intermediate longitudinally disposed rib 14 for the reception of the partition 8 thereby to prevent 80 accidental displacement of the same. 85

The intermediate portion of each plate 11 is bent inwardly to produce a longitudinal reinforcing rib 15 defining a seating groove 16 for the reception of the central window stop 17. The window stop 17 is preferably 90 constructed from a single piece of sheet metal bent to form oppositely disposed contact lips 18 terminating in a reduced shank 19, which latter is seated within the groove 16 and is retained in position on the window 95 frame by screws or similar fastening devices 20. The screws 20 are disposed at spaced intervals on the window stop and are threaded in suitable openings 21 formed in the reinforcing bead 15 thereby to firmly clamp the 100 stop 17 in engagement with the window frame. The inside window stop 22 is similar in construction to the central stop 17 and is also retained in position on the window frame by one or more screws 23. 105

The reinforcing plate 11 is off set at the inside of the window frame and the metal comprising the inner section of the window frame extended outwardly at the off set portion 24 to form reinforcing beads 25 and 26, 110 which latter are spaced apart to permit the introduction of the shank of the inside stop 22.

A longitudinal rib or flange 27 is extended laterally from the reinforcing plate 11 and is provided with a terminal head or lip 28 which corresponds to the lips 18 of the central stop 17, said flange constituting the outside stop of the window and being so arranged as to bear against the adjacent side rail of the upper sash 6.

The sliding sashes 6 and 7 are also preferably hollow and constructed of sheet metal, the longitudinal edges 29 of the side rails of the sashes being extended laterally to form inclined guide flanges 30 which over-lap the edges of the metal constituting the body of the sash and are riveted, welded or otherwise rigidly secured thereto. The longitudinal edges of the sliding sashes are spaced from the inner faces of the window frame or casing to form an intermediate air chamber or cushion 31, there being loops or eyes 32 secured to the longitudinal edges 29 of the sashes for engagement with a chain or other flexible connection, indicated at 32'. The chains 32' pass over suitable pulleys 33 and are extended downwardly within the compartments 9 for attachment to the weights 10 thereby to counter-balance the sashes.

Attention is here called to the fact that the flanges 30 bear against the shanks of the adjacent window stops while the lips 18 and 28 bear against the adjacent walls of the sliding sashes thus reducing friction between the parts to a minimum, while at the same time permitting a close fitting sash which is practically weather proof.

The lintel 34 of the frame or casing is also reinforced and strengthened by a metallic plate 35, there being spaced depending ribs 36 formed on the bottom of the plate 35 and 40 between which the upper sash 6 is seated when said sash is in closed position, as best shown in Fig. 6 of the drawings.

The top rail of the upper sash 6 is provided with a sheet metal cover or cap piece 37 having its opposite longitudinal edges bent to form depending flanges 38 which engage seating grooves formed in the metal comprising the body portion of said sash, the walls of the seating grooves being extended laterally beneath the plate or cap 37 to form supporting flanges 39.

As a means for locking the plate or cap piece 37 in position on the upper sash there is provided a screw 40 carrying a turn button 41 which bears against the flanges 39 when the screw is rotated thereby to lock the parts in assembled position.

Extending vertically from and preferably formed integral with the reinforcing plate of 60 the lintel 34 are spaced brackets 42 in which is mounted a shaft 43 carrying the pulleys 33, the latter being mounted for independent rotation on the shaft 43, as shown.

The base or sill 44 of the window frame or 65 casing is preferably filled with cement, con-

crete or other plastic material and is provided with a plurality of stepped shoulders 45, one of which is adapted to receive the lower transverse rail of the sash 7 when the latter is in closed position.

The metal forming the lower rail of the sash 7 is extended downwardly beyond the base 46 of said sash to produce a depending lip 47 which engages the inclined shoulder 48 of the sill thereby to assist in preventing the entrance of air or moisture between the lower sash and sill.

The lower sash is also preferably provided with a suitable handle or finger piece 49 by means of which the lower sash may be moved to raised or lowered position.

The metal forming the base of the meeting rail of the upper sash 6 is extended laterally to produce a horizontally disposed flange 50 which bears against the inclined face 51 of the meeting rail of the lower sash 7 when said sashes are in closed position thereby to form an intermediate air chamber or cushion 52 at the juncture of said sashes so as to render the same weather proof.

The meeting rail of the lower sash is reinforced by the provision of a plate preferably in the form of an angle iron 53, which latter extends the entire width of the sash and forms a support for one element of a suitable locking device 54, the other element 55 of the locking device being supported by a reinforcing plate 56 secured to the meeting rail of the upper sash 6.

The muntin 57 is provided with the usual 100 seating grooves for the reception of glass or other transparent material 58.

While it is preferred to construct the window with sliding sashes each having a weight or counterbalance, it is obvious that the 105 weights may be dispensed with and the sashes connected by a cord, chain or other flexible medium so as to balance each other.

The window frames may be made in different sizes and shapes and the metal 110 stamped, embossed or otherwise pressed or formed with ornamental designs so as to give the window a neat attractive appearance.

From the foregoing description it will be seen that there is provided a window which 115 is strong and durable in construction and thoroughly efficient in operation and which is practically weather and fire proof.

Having thus described the invention what is claimed is:

1. A window including a frame having a sill provided with an inclined shoulder, stops secured to the frame, sashes slidably mounted between the stops and provided with guide flanges disposed obliquely to the vertical faces of the sashes for engagement with the stops, a flange depending from the lower sash and adapted to engage the inclined shoulder of the sill when said sash is in closed position, the meeting rail of the lower 130

sash being inclined or beveled, and a flange extending laterally from the meeting rail of the upper sash and adapted to bear against the inclined face of the meeting rail of the 5 lower sash when said sashes are in closed position.

2. A window including a frame, stops secured to the frame, sashes slidably mounted between the stops and provided with guide 10 flanges disposed obliquely to the vertical faces of the sashes and adapted to bear against the stops, the meeting rail of one of the sashes being provided with an inclined face, a flange extending laterally from the 15 meeting rail of the other sash and adapted to bear against the inclined face when the sashes are in closed position, and reinforcing plates carried by said meeting rails.

3. A window including a hollow sheet 20 metal supporting frame, reinforcing plates disposed on opposite sides of the window frame, stops secured to the reinforcing plates and provided with laterally extending lips, sashes slidably mounted between the 25 stops and bearing against said lips, and flanges carried by and disposed obliquely to the vertical faces of the sashes and engaging the stops in advance of the lips.

4. A window including a hollow sheet 30 metal supporting frame, reinforcing plates disposed on opposite sides of the frame, a horizontal reinforcing plate extending across the top of the frame, stops extending laterally from the side reinforcing plates, sashes 35 slidably mounted between the stops and provided with guide lips disposed obliquely to the vertical faces of the sashes and adapted to engage said stops, and ribs depending from the horizontal reinforcing plate and 40 adapted to accommodate the upper sash between them when the latter is moved to closed position.

5. A window including a hollow frame, reinforcing plates secured to the opposite 45 sides of the frame, partitions extending transversely across the frame and defining independent compartments, stops extending laterally from the reinforcing plates and provided with lateral lips, sashes slidably 50 mounted between the stops and provided with lateral guide flanges adapted to engage the stops, a horizontal reinforcing plate extending across the top of the frame, brackets secured to the horizontal plate, pulleys 55 journaled in said brackets, weights slidably mounted in the compartments, and a flexible medium secured to each weight and having its intermediate portion engaging the adjacent pulley with its terminal fastened to one of 60 the sliding sashes.

6. A window including a frame, sashes 65 slidably mounted in the frame and each

having hollow metallic side and end rails, the metal forming the upper rail of each sash being bent inwardly to form laterally 65 extending flanges, cap plates forming a part of the top rails of the sashes and bearing against said flanges, screws carried by the cap plates, and turn buttons engaging the threads on the screws and bearing against 70 said flanges.

7. A window including a frame, reinforcing plates secured to the opposite sides of the frame, a flange extending laterally from each reinforcing plate at the outside of the 75 frame and having its terminal portion bent laterally to form a lip, a stop arranged at the inside of the frame and secured in position on the adjacent reinforcing plates, the metal forming the intermediate portion of 80 the plates being bent inwardly to produce a rib defining a longitudinal seating groove, a central stop formed of a sheet of metal bent to produce oppositely disposed lips terminating in a shank seated within the groove, fastening devices for securing the central stop in position on the reinforcing plate, and sashes 85 slidably mounted between the stops and engaging the lips on the latter, and lateral flanges carried by the sashes and engaging 90 the stops in advance of said lips.

8. A window including a frame, reinforcing plates disposed on opposite sides of the frame and each having one longitudinal edge thereof off set, an intermediate portion 95 of each plate being provided with a longitudinal rib defining a seating groove, an outside stop rib formed integral with each plate, an inside stop rib secured to the plate and provided with laterally extending lips, 100 the material forming the frame at the off set portion of the plate being extended outwardly to form a bead at the inside stop, an intermediate stop having similar lips and provided with a shank seated within the 105 groove of the rib, sashes spaced from the adjacent reinforcing plates to produce an air chamber, said sashes being slidably mounted between the lips of the stops and provided with inclined guide flanges adapted 110 to engage said stops, the meeting rail of one of the sashes being provided with an inclined face and the meeting rail of the adjacent sash formed with a flange adapted to engage said inclined face when the sashes are 115 in closed position.

In testimony that I claim the foregoing as my own, I have hereto affixed my signature in the presence of two witnesses.

BARTOW A. WARLICK.
